UNITED STATES PATENT OFFICE.

HERBERT E. NOON, OF NEWARK, NEW JERSEY, ASSIGNOR TO THE SINGER MANUFACTURING COMPANY, A CORPORATION OF NEW JERSEY.

NEEDLE-Straightening MACHINE.

1,125,706.

Specification of Letters Patent.

Patented Jan. 19, 1915.

Application filed June 7, 1911. Serial No. 631,687.

To all whom it may concern:

Be it known that I, HERBERT E. Noon, a citizen of the United States, residing at Newark, in the county of Essex and State of New Jersey, have invented certain new and useful Improvements in Needle-Straightening Machines, of which the following is a specification, reference being had therein to the accompanying drawings.

10 This invention has for its object to provide a simple and effective mechanism for straightening light bars or wires, and particularly sewing machine needles, and the following description relates more particularly to the straightening of sewing machine needles subsequent to the tempering operation.

In its preferred form, the improvement comprises a plurality of separated rigid supports one of which is movable toward and 20 from the other and is provided in its operative face with a needle-shank recess or pocket serving as a bearing within which the shank of the needle is revolvably held by a spring-pressed rotator applying a substantially invariable yielding and resilient pressure thereon to maintain the needle-blade spaced slightly above the face or operative edge of the stationary support or anvil. A straightener in the form of a rapidly reciprocating hammer operates upon 25 the needle-blade between said supports and constantly close to the stationary support. The position of the needle in being straightened is thus gaged by the contact of its rotating shank upon the walls of its recess and the needle is sustained similarly to the manner in which it is held in the needle-clamp of a sewing machine, while the straightening operation is performed progressively 30 upon the needle-blade from the shank to the eye by a series of regulated impacts of the hammer proportionate to the eccentricity of the needle relative to the axis of its shank.

A stationary needle-hopper is mounted at 45 one side of the movable needle-support with its bottom at substantially the same level therewith, and needles are successively conveyed from the hopper to said support by an inserter comprising a reciprocatory slide- 50 plate affording a bottom for the hopper and provided with a needle-cavity registering alternately with the interior of the hopper and with a needle-shank receiving recess or pocket formed in the upper face of the needle-support. The needle-conveying slide-

plate has pivotally connected with its outer portion an ejector consisting of a pair of fingers adapted to engage a needle within the needle-recess to remove a straightened needle therefrom simultaneously with the 60 conveyance thereto of an unstraightened needle from the hopper.

The action of the hammer is governed by an impact-regulator which is preferably controlled in its operation by a feeler contacting with and partaking of the eccentric movements of the needle at the bend or eccentric portion close to the stationary support or anvil and upon the side thereof opposite the hammer. To this end, the hammer has rigidly connected to it, so as to partake of its reciprocatory movements a movable stop-member which is for convenience herein termed a striker, between which and a fixed abutment or thrust-block is interposed a transversely movable space-block preferably in the form of a wedge and sustained by a vibratory arm fixed to a rock-shaft to which is rigidly secured a feeler-arm formed of relatively yielding members 80 each carrying one of the component sections of the needle-engaging die. The vibratory movements of the feeler-arm derived from the rotation of the bent needle-blade or other article to be straightened are communicated 85 to the space-block affording the active member of the impact-regulator and whose position intermediate the striker and the stationary abutment determines the point at which the operative movements of the hammer are 90 arrested corresponding in extent with the degree of deflection or eccentricity of the needle or other article.

It has been found in practice in the tempering of needles that the distortion due to successive heating and rapid cooling is greatest at the points where differences in thickness occur, viz., at the junction of the blade with the shank and at the eye, while in the intermediate portion the distortion is 95 comparatively slight. Owing to the small amount of deflection of needles having even the maximum degree of distortion received under actual working conditions, and the extremely small power possessed by the needles to actuate the impact-regulator, the effective action of the hammer can be automatically controlled only within a comparatively limited range of adjustment. Furthermore, it has been found impracticable, 100 105 110

without materially increasing the complexity of the mechanism, to time the hammer-blows so that they shall be delivered invariably in exact register with the extreme point of deflection of the needle. Accordingly, instead of adjusting the machine to deliver one or more straightening blows in exact register with the bend or crook to be removed, at or intermediate the extremities of the blade during the rotation of the needle, the mechanism is constructed to produce in each cycle a comparatively large number of relatively light blows in quick succession, the period of action of the hammer and the lengthwise feed of the needle being so timed that a primary series of regulated blows is delivered upon the blade adjacent the shank while the needle continues to rotate, so that a sufficient number of impacts is delivered in such portion of the needle to perform the straightening action cumulatively. A further series of blows is distributed along and around the blade in such manner as to remove any deflection therein intermediate the shank and a point near the eye, at which point the feed of the needle is again arrested for delivery of a final series of concentrated regulated blows around the circumference of the needle-blade adjacent the eye, preferably somewhat greater in number than the primary series of blows, with an effect at such point similar to that previously produced adjacent the shank.

The present improvement will be more fully understood by reference to the accompanying drawings, in which—

Figure 1 is a sectional elevation of the needle-straightening machine, and Figs. 1^a and 1^b are details of parts of the friction-wheel driving mechanism and Fig. 1^c is a perspective view of the hammer-head. Fig. 2 is a plan of the machine and Figs. 3 and 4 are respectively an end view and partial transverse section thereof. Fig. 5 is a perspective view of the needle delivery chute and holding receptacle, showing the needle-support extension 151 in advance position and in operative engagement with the finger 159 of the needle-detaining gate 206. Fig. 6 is a perspective view of the hammer-shaft with the striker and a portion of the hammer-helve. Fig. 7 is a perspective view of a portion of the bed of the machine with the anvil and needle-carriage and adjacent parts, Fig. 8 a similar view representing the needle-carrier and ejector and the needle-support, Fig. 9 a perspective view of the forward portion of the needle-carrying slide-plate, taken from the lower side, and Fig. 10 a perspective view of the needle-support and ejector. Fig. 11 is a perspective view of the needle-hopper taken from the lower side. Fig. 12 is a perspective view of the space-block with its carrying lever

and means for controlling the position of the same, Fig. 13 a perspective view of the feeler-arm and the sectional die supported thereby, Fig. 14 an outer face view of the sectional die, and Fig. 15 an elevation representing the means of adjustment of the component spring members of the feeler-arm. Fig. 16 is a perspective view of the upper portion of the stop-bar for arresting the hammer action. Figs. 17 and 18 represent developments of the hammer controlling and feed-cams respectively. Fig. 19 is a plan and Fig. 20 an elevation representing a modification of the hammer-stroke controlling means.

The machine is constructed with a frame comprising the base-plate 1 to which are secured by means of screws 2 the feet 3 of the end standards 4 which support the bed 5 sustaining the various operative parts of the mechanism. Secured to the lower side of the bed 5 are the bearings 6 in which is journaled the cam-shaft 7 having fixed thereon the worm-wheel 8 meshing with the worm 9 secured upon the transverse main-shaft 10 mounted in bearings 11 secured upon the base-plate 1. Loosely mounted upon the main-shaft is the hub 12 of the grooved belt-wheel 13 which is encircled by a belt 14 from the source of power for rotating the main-shaft.

The rearward end of the hub 12 is formed with a projecting clutch-tooth 15 adapted for engagement with the similar clutch-tooth 16 upon the adjacent face of the grooved belt-wheel 17, whose hub 18 is fixed upon the main-shaft, and which is embraced by a belt 19 running over the grooved belt-wheel 20 fixed upon the transverse hammer-actuating shaft 21 journaled in the spaced bearing standards 22 extending upwardly from one end of the bed 5. The forward end of the hub 12 of the driving belt-wheel 13 is formed with an annular groove 23 entered by the flattened head 24 of the shift-lever 25 pivotally mounted by means of the stud-screw 26 upon the post 27 rising from the base-plate 1 and affording a means of shifting the pulley 13 endwise of the driving shaft for effecting the engagement and disengagement of the clutch-members 15 and 16 so as to connect and disconnect the machine and its source of power at the will of the operator.

The hammer-actuating shaft 21 has fixed thereon the hub 28 of the cam-wheel or trip 29 formed with a series of peripheral teeth 30 having inclined outer faces to effect a wiping engagement with the concavely curved adjacent edge of the arm 31 having a split hub 32 rigidly secured by means of the clamp-screw 33 upon the hammer rock-shaft 34 journaled in the bearing standards 22 parallel with the actuating shaft 21, said hub having projecting laterally therefrom

opposite the arm 31 a second arm 35 formed in its upper side with the spaced notches 36 to receive the loop 37 at the upper end of a tension spring 38 whose lower end is attached to a staple 39 upon the bed 5. The spring 38 serves to yieldingly maintain the arm 31 in operative relation with the hammer-retracting cam-wheel 29 and to impart to the hammer a peening impact. As shown in detail in Fig. 6, the hammer rock-shaft 34 has formed integral therewith the block 40 having a lateral wing 41 to afford a striking shoulder 42, to be later referred to, and a forward extension 43.

The split hub 44 of the hammer-helve 45 is formed with the spaced ears 46 drawn together by means of the screw 47 to clamp the same upon the hammer-shaft 34, and the outer end of the helve has adjustably secured thereon the hammer-head 48 with flattened operative portion or nose 49, the hammer-head being formed with a slit leading into the aperture for the helve, and a clamp-screw 48* being applied transversely of said slit. The flattened upper side of the helve 45 adjacent the hub lies beneath the extension 43 of the block 40 and is secured thereto by means of the screw 50 passing through the part 43 and tapped into the helve, an adjusting screw 51 being tapped through the extension 43 and its point resting upon the top of the helve. By manipulation of the screws 47, 50 and 51 in a well known manner the position of the hammer-head relative to its shaft 34 may be adjusted.

Adjacent the path of reciprocatory movement of the hammer is disposed the anvil or blade-support 52 formed with a wedge-shaped blunt upper extremity 53 and provided at the lower end with a flange 54 having tapped through it the adjusting screw 55 whose point rests upon the top of the bed 5. The anvil 52 is fitted within a channel in the bearing block 56 in which it is secured by means of the clamp-screw 57 passing through a slot 58 in the bearing block and tapped into the anvil. The bearing block 56 is provided with the laterally extending feet 59 formed with the elongated apertures 60 entered by the shanks of the fastening screws 61 by which the bearing block is secured upon the bed 5 for adjustment both endwise and crosswise of the operative face of the anvil, the slots 60 exceeding somewhat in width the diameter of the screws 61.

The end portion of the bed 5 opposite that supporting the hammer rock-shaft is formed upon its upper side with a longitudinal guideway 62 with marginal guide-bars 63 secured thereon by means of the screws 64 to overhang said slideway, within which latter is fitted the sliding carriage 65 from which depends through a clearance slot 66 in the bed a stud 67 having the anti-friction

roller 68 which enters the cam-groove 69 in a cam-cylinder 70 fixed upon the cam-shaft 7, and from which the carriage receives its to-and-fro traveling movements longitudinally of the bed.

The shape of the cam-groove 69 will be seen by reference to Fig. 18, wherein the straight portion 69^a constitutes the initial dwell for presentation of the needle-blade adjacent the shank to the hammer for a succession of straightening blows in the advance position of the needle over the anvil or needle-blade support, the inclined portion 69^b produces the lengthwise feed of the needle for distribution of the hammer blows 80 along the needle-blade, and the straight portion 69^c arrests the feed of the needle to present that portion of the blade adjacent the eye for a final series of hammer blows.

After the arrest of the hammer reciprocations, the roller-stud 68 enters the abruptly inclined portion 69^d of the cam-groove to produce the final retrograde movement of the needle to extreme retracted position wherein it is maintained by the straight portion 69^e while the straightened needle is ejected from the movable support or holder and an unstraightened needle inserted therein, after which the traverse of the roller-stud 68 through the abruptly and reversely inclined cam-groove portion 69^f causes the advance of the needle to extreme position over the anvil wherein it is maintained by traverse of the roller-stud within the dwell portion 69^a to receive the initial straightening blows adjacent the shank. The dwell portions 69^a and 69^c while represented as disposed in planes perpendicular to the axis of the cam-cylinder 70, are not necessarily so related to the planes above mentioned, as a slight inclination thereof so as to correspondingly distribute the concentrated primary and final series of straightening impacts near the opposite ends of the needle-blade in contrast with the intermediate distributed series of blows may be found desirable under certain circumstances, and with needles of certain tempers. It is obviously immaterial whether the feeding movements derived from the cam-cylinder 110 115 120 125 130 135 140 145 150 155 160 165 170 175 180 185 190 195 200 205 210 215 220 225 230 235 240 245 and thus provided with outwardly and upwardly inclined forward and rearward walls to facilitate the lateral introduction and removal of the needle-shanks. The bushing 75 is secured in position by means of a clamp-screw 77 tapped into the block 74 with its point engaging a wearing strip 78 interposed between the same and the adjacent edge of the bushing. One of the upper corners of the block 74 is cut away to form the longitudinal groove 79 transverse to the pocket 76, and to the adjacent edge of the block is secured by means of the screws 80 the stop-plate 81 whose upper edge is substantially flush with the top of the bushing 75 and which forms with the notch 79 a runway transverse to the pocket 76 the function of which will be presently described.

The needle-support afforded by the block 74 and its bushing 75 serves to sustain the shank of the needle at one side of the path of the hammer, while the anvil affords a support for the needle-blade adjacent and at the opposite side of the hammer-path. While the traveling needle-support is herein shown and described as affording a means of producing a relative feeding movement between the needle and the hammer, it is evidently immaterial to the present invention which of these members receives the actual feeding movement so long as their relation is so controlled in the operation of the machine as to effect the exposure to the action of the hammer of different portions of the needle-blade throughout that portion of its length between the eye and the shank.

Disposed above the needle-shank pocket in the bushing 75 is the rotary friction-wheel 82 formed with a yielding facing such as that afforded by rubber or leather, this friction-wheel being secured upon one end of a shaft 83 whose axis is inclined slightly to the needle-shank pocket 76 and to the direction of travel of the carriage 65. Secured upon the carriage adjacent the needle-support is the foot 84 of the bearing bracket 85 formed with a vertical guideway 86 in which is fitted the vertically movable journal-box 87 for the adjacent end of the friction-wheel shaft 83, the bearing bracket being provided above the same with an upright socket 88 having in its upper end a screw-plug 89 with lock-nut 90 between which and the top of the box 87 is interposed the spring 91 acting through the shaft 83 to press the friction-wheel 82 toward the bushing 75 and into operative engagement with the shank n' of a needle n disposed in the groove or pocket 76. The opposite end 60 portion of the shaft 83 is formed with a longitudinal groove 83^x entered by a spline 92 secured by means of transverse pins 93 within a bushing 94 slidingly fitted upon the shaft and formed with a neck 95 which is loosely fitted to an aperture in the tilting bearing

block 96 pivotally mounted by means of the pin 97 within a fork in the upper end of the post 98 rising from the bed 5. Upon the reduced outer end of the bushing 94 is secured by means of the nut 99 the pinion 100 locked against rotation thereon by means of the spline 92 and meshing with the intermediate gear 101, which meshes in turn with the actuating gear 102 fixed upon the outer end of the cam-shaft 7. The connection between the shaft 83 and the bearing block 96 is sufficiently loose to enable the shaft to slightly change its angular relation with the carriage under the influence of the to-and-fro longitudinal movement of the journal-box 87.

In order to permit the introduction and removal of needles in the pocket 76, provision is made for temporarily retracting the friction-wheel 82 in opposition to its spring. The journal-box 87 has a lateral extension 87^x beneath which extends one arm 103 of a yoke-lever fulcrumed upon the stud-screw 104 intermediate the spaced bearing lugs 105 of the bed and provided with a second arm 106 formed with a depending nose-piece 107 having a backwardly and downwardly inclined operative edge adapted for engagement with the cam 108 fixed upon the cam-shaft 7 adjacent the cam-cylinder 70 and provided with a peripheral tooth or projection 109 adapted by its engagement with the nose-piece 107 of the lever-arm 106 to lift the same and maintain it elevated for a short period in each rotation of the cam-shaft, thereby engaging the lever-arm 103 with the journal-box 87 and causing the retraction of the friction-wheel from engagement with the needle-shank. Ample clearance is thus provided for removal of the straightened needle and introduction of the unstraightened needle preparatory to a succeeding straightening operation.

To prevent the descent of the friction-wheel 82 into contact with the needle-support, the bearing bracket 85 has secured adjustably thereto by means of the screw 110 passing through a slot 111 the stop-plate 112 having a flange 113 adapted for engagement with the adjacent end of the journal-box 87 so as to limit its downward movement under the action of the spring 91.

The bed 5 is provided with a lateral extension 5^x upon which is secured by means of the screws 114 the platform 115 provided along the edges with the ribs 116 to form a channelway to receive the edges of the reciprocating needle-carrying slide-plate 117 constituting the inserter which is sustained by said platform and having secured to its under face the shank 118 of the needle-sustaining finger 119 moving in the longitudinal groove 120 in the upper face of said platform. The forward portion of the slide-plate 117 is provided with a needle-cavity 130

in the form or a transverse slot 121 between which and its forward edge said plate is cut out in its under face to form a needle-clearance space 122. The slot 121 has its rearward upper edge cut away to form a bevel 121* (Fig. 8) extending from one end to a point midway of its ends and of gradually diminishing depth, the bevel being formed in a plane inclined to the length of the slot and to the upper face of the slide-plate, for a purpose presently to be described.

The slide-plate 117 is formed at its rearward end with the spaced bosses 123 with an intermediate slot 124 within which is supported upon the pivotal pin 125 the roller 126 which is embraced by the fork 127 at the upper end of one arm 128 of an angle-lever mounted upon the fulcrum screw-stud 129 sustained by the forked bearing block 130 upon the base-plate 1, said angle-lever having a second arm 131 carrying a roller-stud 132 maintained in engagement with the periphery of a cam-wheel 133 fixed upon the cam-shaft 7. The cam-wheel 133 has in its periphery a substantially V-shaped recess 134 extending inwardly nearly to its supporting shaft 7 and a series of indentations 135 at another part of the circumference, the roller-stud 132 being caused to follow the contour of the cam by means of the spring 136 connected at one end with a pin 137 upon the lever-arm 128 and at the other, end to a fixed pin 138 depending from the bottom of the bed 5. The rocking movements imparted to the angle-lever by means of the cam-wheel 133 and spring 136 are communicated to the slide-plate 117 which receives therefrom for each rotation of the cam-shaft a full-stroke reciprocatory movement followed by a series of partial-stroke reciprocations whose objects will later appear.

The platform 115 is formed with lateral notches 139 to receive the depending extensions 140 of the parallel side-plates 141 of the needle-hopper connected by the converging end plates 142 whose lower ends extend downwardly to the upper face of the slide-plate 117 which has at its forward end a lateral extension 117* moving in a slot 141* of one of the side-plates 141. The slide-plate thus affords a movable bottom for the hopper and in its full-stroke reciprocatory movements serves to carry laterally from the hopper needles dropping successively into the slot 121 forwardly over the platform 115 and into the needle-pocket 76 of the needle-support whose upper face is at the same level and continuous with said platform.

The short jogging movements of the slide-plate or needle-carrier 117 are performed near its retracted position with the needle-slot or cavity 121 intermediate the lower

edges of the end plates 142 of the hopper, and these jogging movements serve to agitate the needles and separate from the mass of needles individual needles for introduction therein for conveyance to the needle-support.

The unstraightened needles are frequently so bent or distorted by the hardening or tempering operation as to occupy a width of space materially greater than the diameter of their shanks, and their blades often become more or less interlocked, in consequence. In order that they may be singly and successively deposited within the cavity of the carrier 117, and to prevent clogging, the lower contracted end of the needle-hopper is preferably made of a width several times greater than the maximum diameter of a needle, so that in the reciprocation of the carrier beneath the mass of needles they may be permitted a certain amount of lateral movement to accommodate themselves to the needle-cavity. It has also been found in practice, that, by providing the inclined bevel 121* at the shank-receiving end of the slot 121, the needle entering the slot has its blade upwardly inclined so that the shank first enters the slot and the blade is enabled to disengage itself from those of the adjacent needles, thereby preventing the clogging of the carrier in conveying the needles individually from the hopper.

Extending upwardly and forwardly from the forward extremity of the slide-plate 117 are the spaced perforated lugs 143 upon which is pivotally mounted by means of the pins 144 the needle-ejector 145 having the forked ejector-fingers 146 and 147, to the latter of which is applied the spring 148 for pressing the same downwardly. The lower edges of the fingers 146 and 147 normally rest upon the upper face of the platform 115 when the slide-plate 117 is retracted, but in the advance of the slide-plate these fingers ride downwardly through the notches 149 and 150 in the forward edge of the platform, the finger 148 traversing the runway 79 extending transversely of the butt ends of the needle-shanks as represented in Fig. 10.

Upon the delivery side of the needle-support and flush with the top of the same is an extension thereof 151 formed with a backwardly projecting needle-supporting finger 152 and with a transverse depression 153, the extension member having a foot-piece 154 secured by means of a screw 155 upon the top of the carriage 65. The inclined upper face of the body 145 of the ejector has secured thereon by means of the screw 156 a needle-retaining spring 157 extending forwardly intermediate the fingers 146 and 147 and so shaped at its outer end as to lightly press the needle upon the top of the needle-

support 74, the finger 152 and extension 151 thereby producing sufficient resistance to the advance of the needle to confine it within the forked operative ends of the ejecting fingers so as to positively control the movement of the needle. As the ejector reaches extreme advance position under the action of the slide-plate 117 in conveying a needle from the hopper to the needle-shank pocket 76, the straightened needle engaged by the ejecting fingers drops into the depression 153 and out of the range of action of the retaining spring 157, and thus rolls by gravity into the delivery chute for conveyance into the receiving tray or receptacle.

As herein shown, the end plates 142 of the hopper are formed with the vertical slots 142* to receive the pressure bar 158 detachably connected with the head 159 of a vertical bar 160 suitably journaled in the bed extension 5* and in practice carrying a weight by means of which a pressure is placed upon the shanks of the needles in the chute so as to maintain the needles in substantially parallel relation to insure their proper delivery to the carrier-plate 117.

Secured upon the bed 5 adjacent one of the bearing standards 22 by means of screws 161 is the foot 162 of an abutment plate 163 formed with an inclined and circularly curved shoulder 164 toward and from which the shoulder 42 of the striker 41 moves upon the shaft 34 during the operation of the hammer. Intermediate the shoulders 42 and 164 is interposed the wedge-shaped space-block 165 constituting the active member of the impact-regulator and which is sustained by means of an elastic stem 166 bent transversely from the outer end of a vibratory lever 167 whose opposite end is formed with a round shank 168 fitted to a transverse aperture 169 in the collar 170 formed integral with the feeler rock-shaft 171 having at its opposite ends the axial pins 172 journaled in central apertures in the bushings 173 secured by means of set-screws 174 in the spaced standards 175 of a controller-bracket 176 having a foot 177 provided with elongated transverse apertures 178 entered by the shanks of the fastening screws 179 by means of which said bracket is adjustably secured upon the bed 5. The shank 168 of the lever 167 is secured adjustably within the aperture 169 by means of the set-screw 180.

Any suitable means may be employed for connecting the wedge-block 165 resiliently with the vibratory lever 167, but it is important that such connection be sufficiently rigid to sustain the wedge-block in its movements along the face of the abutment 164 so as to avoid any frictional resistance to such movement. As shown more particularly in Figs. 1 and 12 the inner face of the space-block 165 is substantially concentric with the controller-shaft 171, and the adja-

cent face of the abutment is similarly curved so as to enable the space-block to move as closely as possible thereto without actually touching it in its movement under the influence of the lever 167.

The rock-shaft 171 has secured thereon by means of the set-screw 181 a block 182 in which is secured a laterally bent radially extending arm 183 carrying the counter-weight 184 secured adjustably thereon by means of the set-screw 185. The offset portion of the arm 183 is embraced between two spaced stop-lugs 186 formed upon an angle-plate 187 adjustably secured upon one of the standards 175 of the feeler-bracket by means of a screw 188 whose shank enters a slot 189 therein. By means of the weighted arm 183 just described, the lever 167 and the space-block 165 are counter-balanced upon the supporting rock-shaft 171, while the step-lugs 186 positively limit the range of movement of the space-block and insure against overthrow under abnormal conditions of control imparted by the action of the hammer upon the needle.

Secured by means of the set-screw 190 upon the rock-shaft 171 intermediate the collar 170 and block 182 is a forked block 191 to the opposite faces of which are secured by means of screws 192 and 193 the elastic shanks 194 of two relatively yielding spring-arms 195 extending lengthwise of the needle and the direction of movement of the carriage and having at their outer ends the alined flanges 196. Each of these flanges 196 is fitted to and secured by means of a fastening screw 197 within a channel formed in the back of one of the component sections 198 and 199 of a die constituting the feeler contact-member and whose relatively tongued and recessed adjacent portions are formed with the substantially round needle-receiving aperture 200 which is outwardly flared to form a conical mouth 201 in the outer face. The spring-arms 195 are sufficiently thin to yield in unison laterally so as to follow the circular movements of the unstraightened needle entering the die, while the elasticity of their shanks 194 permits the separation of the die-sections normally held together thereby, and thus adapts them to accommodate a needle-blade of larger than normal size to provide for emergency in case needles of different sizes should be by accident associated in the same charge of the hopper.

As will be evident by reference to the drawings, the feeler is preferably arranged at the side of the anvil or stationary needle-support opposite the path of movement of the hammer and its component members are adapted to contact with the opposite sides of the needle-blade close to the anvil, with the upper member thereof engaging the same side of the needle-blade as the hammer.

In order to provide for the adjustment of the spring arms 195 toward and from each other, the block 191 is shown in Fig. 15 with the portions of its opposite faces adjacent 5 the screws 193 slightly convergent, so that by turning these screws in, one or the other direction the distance between the arms may be varied. The screw-apertures in the flanges 196 to accommodate the screws 10 197 are made of elongated form so as to permit the adjustment of the die-sections upon their respective carrying arms to compensate for wear resulting from long continued use. By removing the screws 197 15 the die-sections may obviously be removed for replacement by others fitted to a different size of needle.

In practice, the needle-holding and straightening members may be properly set 20 for effective operation by first inserting a perfectly straight needle in the holding support 74 and advancing the carriage to bring the needle-blade above the anvil; then adjusting the top or operative edge of the 25 anvil a few thousandths of an inch below the lower side of the needle-blade, and finally setting the hammer upon its rock-shaft 34 by means of the adjusting screws 50 and 51 to bring the point or nose of the 30 hammer-head just into contact relation with the top of the needle-blade. When the hammer is at rest in its extreme lower position, it is thus set at a point slightly more removed from the plane of the face of the 35 anvil than the diameter of the needle-blade. The hammer is successively lifted and released by engagement of the arm 31 with the peripheral teeth of the tripping cam 29, the hammer-head being lifted to the same 40 point in each retractive movement and performing its operative stroke under the influence of its own weight augmented by the action of the spring 38 until forcibly arrested by engagement of its striker with the 45 space-block interposed between the same and the fixed abutment or thrust-block 163. The gyratory movements of the unstraightened needle passing through the die over and adjacent the anvil impart to the feeler-arm 50 vibratory movements which are communicated to the lever 167 transmitting to the space-block its operative reciprocatory movements. The position of the space-block obviously determines the stopping position 55 of the shoulder 42 of the striker relative to the fixed shoulder 164 and thus determines the extent of the effective stroke, and hence the effectiveness of the blow struck by the hammer. As the determination 60 of the hammer-stroke is by this means delayed until actually the instant that the blow is delivered to the needle, and as the control of its stroke is regulated by the deflection of the needle from its axis at the 65 same instant and upon the diameter of the

needle parallel with the direction of movement of the hammer, it will be seen that without interrupting the uniform rotation of the needle the hammer impact is positioned and governed with the greatest precision. 70

As the die continues to closely embrace the portion of the needle-blade upon the opposite side of the anvil while the blow is struck by the hammer, the needle-blade is 75 thus sprung to an abnormal degree which in practice has a tendency to produce a very material overthrow of the space-block from which it might be unable to recover before the next blow of the hammer. The yielding character of the upper feeler-arm 195 enables it to act as a recoil absorber which accommodates in the feeler itself the abnormally rapid changes in the deflection of the needle produced by the impact of the 80 hammer thereon and prevents their being transmitted to any considerable extent to and causing the excessive overthrow of the active member 165 or 232 of the impact regulator. By employment of the stop-members 85 186 the lever 187 is prevented from performing such abnormal movement, and the control of the space-block is not therefore materially impaired by the blow of the hammer upon the needle undergoing the 90 straightening operation. 95

Suitably secured upon the bed 5 is the inclined chute 202 extending forwardly from the needle-support extension 151 and provided with the side flanges 203 to which are pivoted by means of the transverse pins 204 the depending ears 205 of the swinging gate 206 formed with the needle-detaining lip 207 normally resting upon the bottom of the chute and serving as a barrier to arrest the straightened needles as they are delivered from the needle-support. The gate 206 has a forwardly extending arm 208 with a downwardly and laterally inclined finger 209 normally depending below the extension-plate 151 but adapted to be engaged by the same in the travel of the carriage to present a needle for the straightening operation, thereby causing the lifting of the gate and raising of the lip 207 to permit the 105 straightened needle previously detained thereby to continue its movement through the chute and into the holding receptacle 210 which is provided on the adjacent side with the hooked lugs 211 engaging the upper edge of a plate 212 suitably secured to the front edge of the bed 5. The object in arresting the movement of the needles between their release from the ejector and arrival in the receptacle 210 is to insure their 110 substantial uniform delivery within the holding receptacle. As the shanks are considerably larger and heavier than the blades, the tendency is for the needles to assume various directions in moving any considerable 115 120 125 130

distance through the chute if the latter is unprovided with means of control such as those herein shown and described.

While the needles are being introduced and removed from the needle-support, and while they are being advanced across the anvil and through the feeler-die to present initially for the straightening action the part of the blade joining the shank, it is requisite that the hammer shall be maintained out of action. Instead of arresting the operation of the hammer-actuating means, this is allowed to continue its action idly at such times, and the hammer is maintained in raised position by engagement of its helve 45 with the notched head 213 of a vertically disposed stop-bar 214 journaled in a tubular bearing post 215 mounted in the bed 5, its wedge-shaped lower extremity 216 being pressed, by means of the spring 214^x attached to the head 213, upon the periphery of a lifting cam fixed upon the cam-shaft 7. This cam is formed in two sections 217 and 218 arranged side by side and formed with substantially circular peripheries with projections 219 and 220, respectively, forming operative portions. The hub 221 of the primary section 217 is secured adjustably upon the cam-shaft by means of the set-screw 222, and the hub 223 of the auxiliary section is fitted upon the hub 221 of the primary section and secured for circular adjustment thereon by means of the set-screw 224. By shifting one of these sections upon the other, the effective length of the operative face of the composite cam thus formed may be lengthened or shortened to produce the requisite period of inaction of the hammer, which is determined by the length of the needle-blade between the eye and the shank.

As represented diagrammatically in Figure 17, the projections 219 and 220 of the sectional cam 217 218 are arranged in register with the portions 69^a 69^b and 69^c of the feed-cam groove 69 in order that the action of the hammer may be interrupted while the rotator 82 is arrested for the release of a straightened needle and subsequent insertion of an unstraightened needle and while the carriage is moving backwardly from the final straightening position and advancing to extreme initial straightening position relative to the anvil. The projections 219 and 220 are obviously adjusted relatively to the cam-shaft 7 and to each other in such manner as to determine the period of action and timing of operation of the hammer to produce the desired number of impacts upon the needle during the initial and final dwells of the same, the number of blows adjacent the needle-eye being preferably somewhat greater than near the shank.

In order to provide for needles of different length from point to butt end of shank,

an adjustable lining plate 225 is applied to one side of the needle-hopper and is formed with an outwardly projecting stud 226 passing through a bearing boss 227 of the adjacent side-plate 141 and secured adjustably 70 therein by means of the set-screw 228.

In the initial positions of the operative parts of the mechanism, the carriage, which sustains the movable needle-support 74 constituting one of the needle-shank gripping members, is retracted, the needle-carrying slide-plate is withdrawn to position its needle-cavity beneath the lower end of the hopper, the other gripping member, consisting of the friction-wheel or rotator, is raised, 80 and the hammer is retained in elevated position by engagement of the stop-bar 214 with the helve 45, all as represented in Figs. 1, 2, 3 and 4. The actuation of the shift-lever 25 to throw the clutch-hub of the continuously rotating pulley 13 into operative relation with the clutch-member of the fixed belt-pulley 17 causes the rotation of the main-shaft 10, the hammer-actuating shaft 21 and cam-shaft 7.

The needle-inserter or carrier 117 now makes a full stroke which carries an unstraightened needle *n* *n'* within its cavity 121 forwardly over the platform 115 toward the needle-support and simultaneously carries the ejecting fingers 146 and 147 to, between and beyond the separated needle-shank gripping members, thus causing them to forcibly engage the blade *n* and shank *n'*, respectively, of the previously straightened 100 needle resting in the groove or pocket 76. As the carrier completes its advance or operative movement, the shank of the unstraightened needle is caused to drop into the pocket 76 with the adjacent portion of its blade 105 resting upon the supporting or steadyng finger 152 of the extension 151. The needle-carrier now retires and the rotating friction-wheel 82 descends into frictional engagement with the needle-shank and rotates it while 110 detained from lateral movement by engagement of the inclined side-wall of its pocket. After the needle-carrier has returned to retracted initial position, the engagement of the roller-stud 132 with the peripheral cavities 135 of the cam-wheel 133 causes a slight jogging movement of the same which acts to separate from the mass of unstraightened needles in the hopper a single needle which drops into the slot 121 preparatory to a 115 succeeding transfer stroke of the carrier. The carriage now makes a quick movement to extreme advance position under the action of the feed-cam 70 so as to bring that portion of the needle-blade adjacent the shank 12 close to the anvil and within the path of the hammer, the point of the needle entering the feeler-die aperture 200. The stop-bar 214 then descends to release the hammer-helve 125 and the hammer begins its operative recipro-

catory movements under the action of the rotating cam 29 controlled in its effect by the space-block 165 whose position for each hammer-stroke is determined by the two-part feeler-arm 195 under the influence of the gyratory movements of the needle.

A modification of the needle-stroke controlling device is represented in Figs. 19 and 20 wherein the block 40 fixed to the hammer rock-shaft 34 is formed with a lateral wing 41 having a curved lower operative edge 42* which, in the striking position of the hammer is formed eccentrically to a fulcrum-pin 229 mounted in fixed bearings 230. The fulcrum-pin 229 has mounted thereon the hub 231 of an angle-lever having an upwardly extending arm 232 whose upper end is adapted to afford a stop for engagement with the operative face 42* of the wing 41, while a laterally extending arm 233 of said lever is formed with a rounded extremity 234 entering a socket 235 in the laterally extending lever 236 whose shank 237 is secured within the transverse aperture of the collar 170 of the feeler rock-shaft 171 by means of the set-screw 180.

In this modification of the improvement, the feeler rock-shaft is oscillated by engagement of the feeler-arm with the needle as in that previously described, and the consequent vibrations of the lever 236 are communicated to the stop-arm 232 of the vibratory angle-lever to bring the point of the same at varying distances from the hammer rock-shaft 3, whereby the effective stroke of the hammer is controlled in a manner similar to that previously described. In this construction it will be observed that the member 232 is the equivalent of the space-block 165, while the fulcrum-pin 229 receives the thrust of the striking member 41 of the hammer and thus performs the function of the thrust-block 163.

The inclination of the axis of rotation of the friction-wheel 82 relative to the needle-recess 76 has a tendency to produce both circular and endwise movements of the needle, the endwise thrust serving to maintain the butt end of the needle-shank firmly pressed against the stop-plate 81 so as to maintain the needle in fixed position upon its traveling support, but it is obvious that this inclination of the needle-rotating means might readily be employed, by omission of the stop-plate, in producing the endwise feeding movements of the needle upon a stationary support without departure from the scope of the present invention. The needle-shank recess is for convenience made in the form of a groove corresponding substantially in diameter with the needle-shank, but it is evident that any suitable means may be provided upon the needle-support for detaining the needle-shank from lateral

movement under the action of the friction-wheel, the function of the depression in the upper face of the needle-support being merely to maintain the needle in position thereon during the straightening operation.

In operation the needle-shank is held resiliently upon its traveling support by the yielding-faced rotating member 82 to enable the needle to accommodate itself to the peening action produced by the impact of the hammer intermediate the relatively movable supports, while the blow is directed upon the needle-blade intermediate such rigid supports. The relation of the cams 69 and 217 is such, however, that the blows of the hammer upon the needle-blade are concentrated around the latter adjacent both the shank and the eye, at the beginning and conclusion of the endwise feeding movements of the needle beneath the hammer.

The cylindrical surface of the needle-shank has a bearing directly upon its support with the blade disposed very slightly above the operative edge of the anvil and rotates in contact with the walls of the cavity in its support during the straightening operation so that the blade is gaged or centered with precision under the action of the hammer relative to the shank, and the needle is thus held during the straightening operation in precisely the same way in which it is ultimately secured in the needle-clamp of a sewing machine for coöperation with a loop-taker in performing the stitch-forming operations.

As the controller or feeler is very accurately counterbalanced so as to impose substantially no resistance to the controlling action of the needle which it embraces, it constitutes practically a floating member capable of following with great freedom and precision all movements of the needle transversely of the latter's axis such as are imparted by bends or eccentricities therein. It is also free to move laterally in a horizontal plane. As the feeler and impact-regulator are mounted upon a unitary support, shown herein consisting of the rock-shaft 171, it is evident that they are caused to move in unison, so that the movements of one are transmitted accurately to the other without the lost-motion which would result from mounting them upon independent supports.

As shown and described herein, the hammer-head 48, the wedge-block 165 of the impact-regulator and the feeler-die 198-199 derive reciprocatory movements in curved paths from the vibratory arms 45, 167 and 195, respectively, by which they are carried, but it is obviously immaterial whether such carrying members have their to-and-fro or reciprocatory movements around fixed axes (as those of their respective supporting rock-shafts), or otherwise.

From the foregoing description it will be seen that the present improvement involves principles of construction and arrangement of the various parts which are susceptible of embodiment in widely different forms and associations of parts, and that the present invention is not therefore limited to the details of construction and arrangement shown and described herein.

10 Having thus set forth the nature of the invention, what I claim herein is:—

1. In a straightening machine, the combination with a plurality of separated needle-supports, means whereby during the straightening operation the needle is turned upon one thereof with its axis in a substantially fixed position by a substantially invariable yielding pressure upon its shank, and a straightener operating between said supports.

2. In a straightening machine, the combination with a plurality of separated needle-supports, means whereby the needle is revolvably held upon one thereof in axially fixed relation with the path of movement of the straightener by a resilient pressure upon its shank, and a straightener operating between said supports.

3. In a straightening machine, the combination with a needle-blade support, of a recessed shank-support separated therefrom, means for rotating the needle-shank in said recess as a bearing, means for restraining the shank support against movement crosswise of its recess, and a straightener operating between said supports.

4. In a straightening machine, the combination with a recessed bearing for the needle-shank laterally stationary relative to the operations on the needle, of means for rotating the needle-shank on said bearing, and a straightener operating upon the needle-blade, whereby the position of the needle in being straightened is gaged by the rotating shank upon the walls of its recess.

5. In a straightening machine, the combination with a bearing laterally stationary relative to the operations on the needle and upon which the needle-shank is rotatable, of a rotator, and a straightener operating upon the needle-blade whereby the position of the needle being straightened is gaged by the contact of the shank upon the bearing on which it rotates.

55 6. In a needle-straightening machine, in combination, a feeler containing two contact members, a spring holding one of said contact members toward the other and an impact regulator connected with said feeler.

60 7. In a needle straightening machine, in combination, a hammer, means for turning the needle, a feeler containing a spring-pressed contact member operated by the gyroscopic movements of the needle-blade, and an impact regulator mechanically connected

therewith and adapted to limit the advance of the hammer toward the needle.

8. In a needle straightening machine, in combination, a hammer, means for turning the needle, a feeler contact member operated by the gyroscopic movements of the needle-blade, a pivotally mounted spring-arm supporting the same, and an impact regulator mechanically connected therewith and adapted to limit the advance of the hammer toward the needle.

9. In a straightening machine, the combination with needle-supporting means, of a hammer, an automatically acting impact-regulator therefor, and a feeler for controlling said regulator and formed with reversely arched jaws embracing and contacting with the needle on opposite sides.

10. In a straightening machine, the combination with needle-supporting means, of a hammer, an impact-regulator therefor, a feeler contacting with the needle-blade, and a substantially unitary support for said feeler and regulator.

11. In a straightening machine, the combination with an anvil, and a hammer, of a feeler at the opposite side of said anvil from the hammer and on the opposite side of the needle-blade from said anvil, an impact-regulator for said hammer, and mechanism connecting the feeler and impact-regulator and containing a recoil-absorber to absorb the recoil produced on the feeler by the impact of the hammer.

12. In a straightening machine, the combination with needle-supporting means, of a hammer, an impact-regulator therefor, and a feeler contacting with the needle for controlling said regulator and mounted to be freely movable in directions transverse to the needle and to each other.

13. In a straightening machine, the combination with a straightener, of separable needle-gripping members, a needle-ejector, a needle-inserter, and means whereby the ejector is moved to, between, and beyond the separated gripping members.

14. In a straightening machine, the combination with a straightener, of separable needle-gripping members, means for imparting to said gripping members movements longitudinally of the needle, a needle-ejector movable transversely of the needle, a needle-inserter, and means whereby the ejector is moved laterally to, between and beyond the separated gripping members.

15. In a straightening machine, the combination with an anvil and a needle-support separated therefrom and affording a bearing for the needle, of a hammer movable in a path intermediate said anvil and needle-support, and means for effecting simultaneously the actuation of the hammer, a relative feeding movement between the hammer and

and the needle lengthwise of the latter, and the rotation of the needle in contact with and in relation to its support.

16. In a straightening machine, the combination with an anvil and a needle-support separated therefrom and affording a bearing for the needle, of a hammer movable in a path intermediate said anvil and needle-support, hammer-actuating means, and means, including a needle-engaging member having a direction of movement eccentric to the axis of the needle, whereby the needle is rotated and relative feeding movements lengthwise of the needle are produced between the needle and the hammer.

17. In a straightening machine, the combination with an anvil, a hammer, and hammer-actuating means, of a needle-support, and a rotary friction-wheel adjacent the needle-sustaining face of said support and having an axis of rotation inclined to the needle.

18. In a straightening machine, the combination with an anvil, a hammer, and hammer-actuating means, of a needle-support, a rotary friction-wheel adjacent the needle-sustaining face of said support and having an axis of rotation inclined to the needle, a stop to receive one end of the needle under the action of said friction-wheel, and means for producing relative feeding movements between the needle-support and the hammer.

19. In a straightening machine, the combination with an anvil, a hammer, and hammer-actuating means, of a needle-support, a rotary friction-wheel adjacent the needle-sustaining face of said support and adapted to engage and rotate the needle, and means for moving said friction-wheel toward and from said needle-sustaining face of the support to permit the introduction and removal of the needle.

20. In a straightening machine, the combination with an anvil, a hammer, and hammer-actuating means, of a needle-support, a rotary friction-wheel adjacent the needle-sustaining face of said support and adapted to engage and rotate the needle, a spring for pressing said friction-wheel toward said support, and automatically acting means for retracting said friction-wheel in opposition to said spring.

21. In a straightening machine, the combination with an anvil, a hammer, and hammer-actuating means, of a needle-support having a laterally open needle-shank pocket, a needle-hopper, a reciprocating carrier-plate having a needle-cavity movable therewith into and out of said hopper and into register with the needle-shank pocket, and means for rotating the needle in said needle-shank pocket.

22. In a straightening machine, the combination with an anvil, a hammer, and ham-

mer actuating means, of a needle-support having a laterally open needle-shank pocket, a needle-hopper, a reciprocating carrier-plate having a needle-cavity movable therewith into and out of said hopper and into register with the needle-shank pocket, actuating means for imparting to the carrier-plate full- and partial-stroke reciprocations for each needle-straightening operation, and means for rotating the needle in said needle-shank pocket.

23. In a straightening machine, the combination with an anvil, a hammer, and hammer actuating means, of a needle-support having a laterally open needle-shank pocket, a needle-hopper, a reciprocating carrier-plate having an open-bottomed needle-cavity movable therewith into and out of said hopper and into register with the needle-shank pocket, a platform beneath the carrier-plate and extending from the needle-hopper to the needle-support and adapted to sustain the needle within said cavity in its conveyance from the hopper to the needle-shank pocket, and means for actuating said carrier-plate.

24. In a straightening machine, the combination with an anvil, a hammer, and hammer-actuating means, of a needle-support having a laterally open needle-shank pocket, a needle-hopper, a reciprocating carrier-plate having a needle-cavity movable therewith into and out of said hopper and into register with the needle-shank pocket, said cavity having an upper edge formed with a bevel extending from one end toward the other of gradually reduced depth, and means for rotating the needle in said needle-shank pocket.

25. In a machine of the class described, the combination with a tool for acting upon the needle, of a needle-hopper having a width at its delivery end sufficient to accommodate a plurality of needles side-by-side, a needle-support, and a carrier affording a bottom for said hopper and movable laterally between the same and said support for conveying needles from one to the other for action of said tool.

26. In a straightening machine, the combination with an anvil, a hammer, and hammer-actuating means, of a needle-support having a laterally open needle-shank pocket formed with an outwardly and forwardly inclined wall on the needle-discharging side, needle-rotating means adapted for engagement with the needle-shank in said pocket, and an ejector adapted to engage the needle and force the same over said inclined wall and out of register with said rotating means.

27. In a straightening machine, the combination with an anvil, a hammer, and hammer-actuating means, of a needle-support provided with a needle-shank pocket, a friction-driver adapted to engage and rotate

a needle-shank within said pocket, automatically acting means for retracting said friction-driver from operative relation with the needle-shank, and automatically acting 5 means for ejecting the needle from said support while the friction-driver is retracted.

28. In a straightening machine, the combination with an anvil, a hammer, hammer-actuating means, a needle-support, and needle-10 rotating means adapted for operative engagement with a needle sustained by said support, of a carrier for placing a needle upon said support in register with said rotating means, and means for ejecting the 15 needle from said support.

29. In a straightening machine, the combination with an anvil, a hammer, hammer-actuating means, a needle-support, and needle-rotating means adapted for operative 20 engagement with a needle sustained by said support, of a carrier for placing a needle upon said support in register with said rotating means, means for ejecting the needle therefrom, and an operative connection 25 between said carrier and ejector whereby they are operated successively to replace one needle upon said support with another.

30. In a straightening machine, the combination with an anvil, a hammer, hammer-actuating means, a needle-support having a 30 laterally open pocket, and needle-rotating means adapted for operative engagement with a needle sustained within said pocket, of a reciprocating carrier for placing a 35 needle within the pocket of said support, and needle-ejecting fingers pivotally connected with said carrier and movable therewith transversely of the needle and adapted to remove the same from said pocket.

40. 31. In a straightening machine, the combination with an anvil, a hammer, hammer-actuating means, a needle-support having a laterally open pocket and an extension beyond and on the delivery side of said pocket, 45 and needle-rotating means adapted for operative engagement with a needle sustained within said pocket, of a carrier for placing a needle within the pocket of said support, a reciprocatory ejector for removing the needle 50 from said pocket provided with needle-engaging fingers and an intermediate spring-retainer adapted to yieldingly retain the needle upon said extension of the needle-support while engaged by the ejector-fingers.

55. 32. In a straightening machine, the combination with a needle-support, an anvil, a hammer, and means for producing relative feeding movements between the needle and the hammer, of a striker having a rigid connection with said hammer and deriving 60 reciprocatory movements therefrom, a stop-member normally disposed within the range of movement of said striker, a fulcrum upon which said stop-member is sustained and

around which it moves, a fixed abutment to 65 sustain the impact of the striker upon said stop-member, and means controlled by the deflection of the needle from its axis for shifting the position of said stop-member to determine the hammer action. 70

33. In a straightening machine, the combination with a needle-support, an anvil, a hammer, and means for producing relative feeding movements between the needle and the hammer, of a stationary thrust-block, a striker having a rigid connection with said hammer and movable therewith toward and from the thrust-block, a space-block interposed between the thrust-block and the striker and adapted for engagement with the latter to arrest its movement, a carrier for sustaining the space-block independently of said thrust-block, and means including a controlling member engaging the needle and actuated by the deflection thereof from its 80 axis for shifting the position of the space-block along the adjacent face of the thrust-block. 85

34. In a straightening machine, the combination with a needle-support, an anvil, a hammer, and means for producing relative feeding movements between the needle and the hammer, of a stationary thrust-block, a striker having a rigid connection with said hammer and movable therewith toward and from the thrust-block, a space-block interposed between the thrust-block and the striker and adapted for engagement with the latter to arrest its movement, a reciprocating carrier 95 with which said space-block has a resilient connection and by which it is sustained independently of the thrust-block, and means controlled in its action by the deflection of the needle from its axis for shifting the position of said space-block to determine 100 the hammer action. 105

35. In a straightening machine, the combination with a needle-support, an anvil, a hammer, and means for producing relative feeding movements between the needle and the hammer, of a striker having a rigid connection with said hammer and deriving reciprocatory movements therefrom, a stop-member normally disposed within the range of movement of said striker, a rock-shaft 110 sustaining said stop-member and around which it moves in a circular path transverse to that of the striker, a fixed abutment to sustain the impact of the striker upon said stop-member, and a vibratory feeler-arm 115 having an operative connection with said stop-member for imparting thereto its reciprocatory movements and carrying a needle-engaging member disposed adjacent said anvil and engaging the needle from 120 which it derives its vibratory movement. 125

36. In a straightening machine, the combination with a needle-support, an anvil, a

hammer, and means for producing relative feeding movements between the needle and the hammer, of a stationary thrust-block, a striker having a rigid connection with said hammer and movable therewith toward and from the thrust-block, a space-block interposed between the thrust-block and the striker and adapted for engagement with the latter to arrest its movement, a vibratory arm upon which the space-block is mounted and sustained independently of the thrust-block, a rock-shaft upon which said vibratory arm is fixed, and a feeler-arm also fixed upon said rock-shaft and provided with means for engaging the needle adjacent said anvil.

37. In a straightening machine, the combination with a needle-support, an anvil, a hammer, and means for producing relative feeding movements between the needle and the hammer, of a striker having a rigid connection with said hammer and deriving reciprocatory movements therefrom, a stop-member normally disposed within the range of movement of said striker, a rock-shaft sustaining said stop-member and around which it moves in a circular path transverse to that of the striker, a fixed abutment to sustain the impact of the striker upon said stop-member, a vibratory feeler-arm having an operative connection with said stop-member for imparting thereto its reciprocatory movements and carrying a needle-engaging member disposed adjacent said anvil and engaging the needle from which it derives its vibratory movements, and stops for determining the extreme positions of said feeler-arm and thus fixing its range of operative movement.

38. In a straightening machine, the combination with a needle-support, an anvil, a hammer, and means for producing relative feeding movements between the needle and the hammer, of a striker having a rigid connection with said hammer and deriving reciprocatory movements therefrom, a stop-member normally disposed within the range of movement of said striker, a rock-shaft sustaining said stop-member and around which it moves in a circular path transverse to that of the striker, a fixed abutment to sustain the impact of the striker upon said stop-member, a vibratory feeler-arm fixed upon said rock-shaft and carrying a needle-engaging member disposed adjacent said anvil and engaging the needle from which it derives its vibratory movements, and an adjustable stop-member adapted to control the range of movement of said rock-shaft and determine the amplitude of such movements.

39. In a straightening machine, the combination with a needle-support, of an anvil adjustable toward and from the same, a

hammer also adjustable toward and from 65 said needle-support, hammer-actuating means, means controlled in its action by the deflection of the needle from its axis for varying the action of the hammer, and means for producing relative feeding movements between the needle and the hammer.

40. In a straightening machine, the combination with a needle-support, of an anvil adjustable toward and from the same, a hammer also adjustable toward and from 70 said needle-support, hammer-actuating means, means for producing relative feeding movements between the needle and the hammer, and means for determining the effective action of the hammer and comprising a vibratory feeler-arm provided with a needle-engaging member adapted to engage the needle, a fulcrum for said feeler-arm, and a support for said fulcrum adjustable toward and from said needle-support.

41. In a straightening machine, the combination with an anvil, a hammer, hammer-actuating means, a needle-support, and means for producing relative feeding movements between the needle and the hammer, 90 of means for determining the effective action of the hammer and including a reciprocally movable carrier and a die adapted to embrace a needle adjacent the anvil, and means for removably securing it to said carrier.

42. In a straightening machine, the combination with an anvil, a hammer, hammer-actuating means, a needle-support, and means for producing relative feeding movements between the needle and the hammer, 100 of means for determining the effective action of the hammer and including a reciprocally movable carrier and a die formed of separable sections and adapted to embrace a 105 needle adjacent the anvil.

43. In a straightening machine, the combination with an anvil, a hammer, hammer-actuating means, a needle-support, and means for producing relative feeding movements between the needle and the hammer, 110 of means for determining the effective action of the hammer and including a reciprocally movable carrier comprising members adapted to yield toward and from each other, 115 and a die adapted to embrace a needle adjacent the anvil and formed in separable sections each attached to one of said yielding members of the carrier.

44. In a straightening machine, the combination with an anvil, a hammer, hammer-actuating means, a needle-support and means for producing relative feeding movements between the needle and the hammer, 120 of means for determining the intensity of 125 action of the hammer and including a reciprocally movable carrier comprising members adapted to yield toward and from each

other and laterally in unison, and a die adapted to embrace a needle adjacent the anvil and formed in separable sections each attached to one of said yielding members of the carrier.

45. In a straightening machine, the combination with an anvil, a hammer, hammer-actuating means, a needle-support, and means for producing relative feeding movements between the needle and the hammer, of means for determining the intensity of action of the hammer and including a reciprocally movable carrier constructed with spring-arms adjustable toward and from each other, and a die adapted to embrace a needle adjacent the anvil and formed in separable sections each attached to one of said spring-arms.

46. In a straightening machine, the combination with an anvil, a hammer, hammer-actuating means, a needle-support, and means for producing relative feeding movements between the needle and the hammer, of means controlled by the deflection of the needle for determining the effective action of the hammer, means for determining the period of action of the hammer during the feeding operation, and means controlled independently of the eccentricity of the needle for varying the length of the period of action of the hammer.

47. In a straightening machine, the combination with an anvil, a hammer, hammer-actuating means, a needle-support, and means for producing relative feeding movements between the needle and the hammer, of means controlled by the deflection of the needle for determining the intensity of action of the hammer, a stop-bar acting inde-

pendently of the hammer-actuating means for interrupting the action of the hammer, and a rotary actuating cam for said stop-bar formed in independent sections mounted for relative circular adjustment to vary the effective length of the operative portion of said cam.

48. In a straightening machine, the combination with an anvil, a hammer, hammer-actuating means, and means for presenting a needle for the action of the hammer, of a needle-ejector, a delivery chute, a normally closed needle-detaining gate therein, and means for opening said gate intermediate successive actuations of the needle-ejector.

49. In a straightening machine, the combination with an anvil, a hammer, hammer-actuating means, means for presenting a needle for the action of the hammer, and means for producing relative feeding movements between the needle and the hammer, of a needle-ejector acting to disengage the needle from its presenting means after each straightening operation, a delivery chute, a normally closed needle-detaining gate therein pivotally mounted transversely to and within the same, and a laterally extending arm connected with said gate and lying within the range of movement of a part actuated by said feeding means whereby the gate is opened once for each feeding action.

In testimony whereof, I have signed my name to this specification, in the presence of two subscribing witnesses.

HERBERT E. NOON.
